UNITED STATES PATENT OFFICE.

FREDERICK JOHN BLAKE, OF WINCHESTER, ENGLAND.

MEANS FOR PREVENTING THE FOULING OF SHIPS' AND LIKE PROPELLER SHAFTS AND PROPELLERS.

Application filed April 19, 1926, Serial No. 103,040, and in Great Britain April 24, 1925.

This invention relates to new or improved means for preventing the fouling of ships' and like propeller shafts and propellers. As is well-known, the propellers and propeller shafts of ships can become fouled very easily by wire and other ropes, and the like, which wind around the propeller shaft and seriously interfere with the propulsion. Trailing and other ropes in harbours, rivers and like waters are, consequently, a menace to the safety of a ship. The object of this invention is to provide an improved device of the kind adapted for preventing the fouling before mentioned and also for severing any rope or flexible or clinging object or matter that may tend to become wound around the propeller shaft or parts thereon, the propeller blades themselves not being relied upon for any shearing action in the performance 10 of the said severance. A further object is to avoid the use of right and left handed parts and to provide a device adapted for effecting the said severance equally well in either direction of revolution.

According to this invention, the guard device comprises serrated cutters adapted for the severance of a rope or the like drawn across or flung against such cutters in either direction. The cutting edges are suitably 20 inclined or curved so as to be adapted for the most efficient cutting action in those directions in which the fouling rope or the like is likely to come within the influence of the propeller. The said serrated cutters are advantageously formed on ribs and these ribs are preferably formed on segments which are bolted on the bearing boss in spaced relation 30 for a purpose hereinafter described.

In order to enable the invention to be readily understood, reference is made to the accompanying drawings, illustrating examples of constructions suitable for use on ships, in which drawings:—

Figure 1 is a side elevation of a propeller 45 and a portion of the stern bracket, the boss of the latter being fitted with cutter devices in accordance with these improvements.

Figure 2 is an end elevation of Figure 1 with the boss of the propeller broken away.

Figure 3 is a perspective view, to a larger 50 scale, of a segment formed with cutter devices and adapted for being fitted to the shaft boss or bracket as seen in Figure 1.

Figure 4 is a perspective view looking up 55 at the underside of Figure 3.

Figure 5 is a central vertical section of the device seen in Figures 3 and 4.

Referring to Figures 1 and 2, *a* is a four-bladed screw propeller the shaft of which runs in the usual bearing or boss *b* of the stern bracket. The guard device comprises a ring of segments *c* which are shown bolted to the boss *b* but which may be welded thereon as by electric or acetylene welding, if desired, or which may be fixed thereon in any other appropriate manner. It is particularly important that, whenever possible, the guard device shall be permanently fixed by welding or otherwise to the hull of the ship and form part thereof and so as not to be liable to be lost at sea owing to vibration caused by the running of shafts which may transmit large powers at high speed. The ring of segments *c* may extend completely around the shaft and they may be spaced apart as shown. Or, the segments may extend around only a portion of the circle. As seen in Figures 1 and 2, and with greater clearness in Figures 3 to 5, each segment is stepped at *d* and across and beyond the step 60 there extends a rib *e* having its outer edge or surface formed as a serrated cutter. Each segment may have a number of such ribs if desired. Looked at from the end, and as seen clearly in Figure 3, the serrated edge may comprise a central ridge of serrations *f* flanked by side ridges of serrations *f'* of less height. The serrated surfaces *f* *f'* may incline or curve towards the centre of the shaft from the rise of the step *d* to the verge thereof, and from this latter point the rib *e* may be extended as at *e'* and also curve towards the centre of the shaft as shown. The free end of the extension *e'* may be formed with 70 a dovetail projection *g* having its top and bottom surfaces hollowed out as at *h* *h'* to produce cutting edges and extending close to the boss of the propellers as seen in Figure 1. The rib extension *e'* may be hollowed out on the underside, as indicated at *e''* in 75 Figures 4 and 5, to form further cutting edges *j* which may be suitably curved and serrated. On either side of each rib *e* and at a suitable distance therefrom, fillets *k* may be provided in the angle of the step *d* 80 and the outer edges of these fillets *k* are formed with serrations *l*. The complete device may be produced in cast steel, and all serrated edges may be hardened and designed and sharpened so as to retain a good 85

100
105
110

cutting capacity for as long a period as possible.

It will now be seen that, between the boss *b* on the hull and the boss of the propeller *a*, there is provided an encircling guard armed with as many serrated cutting edges as possible. Thus, if a rope should be flung by the propeller around the guard or if a rope be dragged over the exterior of the guard in either direction, it will encounter one or more serrated cutting edges and will be severed before any winding up of such rope can occur to the extent of causing the propeller *a* to be fouled. On the other hand, in the event of the end of a rope entering within the guard, the rotary movement will bring such end into contact with the serrated cutting edges *j* on the inner side of the ribs *e*, and severance will be effected as before.

The spaces between the segments *c* serve for giving access for the introduction and driving of wedges when this is necessary for removing the propeller *a* from its shaft, or for gauging the wear of the shaft and its bearings, or for removing the shaft, bearing and liner fitted in the stern of the ship. Further, the guard is so arranged that there are no enclosed spaces in which water and air can be whirled around in close proximity to the shaft and propeller, so that corrosion and erosion which occur when other rope guards are fitted are avoided by the adoption of the present device.

It will be apparent that the details of construction such as the form and disposition of the serrated cutting edges and the construction of ribs *e*, fillets *k* and the like for carrying the cutting edges, are capable of being considerably varied without departing from the invention. In one respect the invention may be regarded as providing a number of serrated cutting edges in proximity to the propeller, these serrated edges being adapted for severing a rope or other entanglement winding in either direction around the shaft. In another respect, the invention may be regarded as providing around the propeller shaft and between the propeller boss and the bearing boss on the hull, an encircling guard having a number of axially or otherwise disposed ribs formed as serrated cutters, the said guard having preferably also internal cutting edges for acting upon any entanglement escaping the guard and the outer serrated cutting edges thereon.

I claim:—

1. Guard device for ships' propellers comprising a segment fixed on the hull and disposed around the propeller shaft, the said segment comprising a plurality of cutter ribs extending longitudinally of the propeller shaft and over the space between the

propeller boss and the stern bearing boss and having cutter serrations on longitudinal edges thereof.

2. Guard device for ships' propellers comprising a segment attachable to a bearing boss, an extension on said segment extending longitudinally in the direction of the axis of the propeller shaft and a serrated cutter formed on a longitudinal edge of said extension.

3. Guard device for ships' propellers comprising a segment attachable to a cylindrical object on the hull, said segment comprising a stepped portion supporting serrated cutters extending in the direction of the axis of the propeller shaft substantially as set forth.

4. For use as a guard device for ships' propellers, a segment of stepped formation, ribs extending over said stepped formation, and cutter teeth formed along said ribs substantially as set forth.

5. For use as a guard device for ships' propellers, a segment of stepped formation, a main rib extending over and beyond the stepped formation, serrated cutter edges on said rib, subsidiary rib formations spaced from said main rib, and serrated cutter edges on said subsidiary ribs substantially as set forth.

6. Guard device for ships' propellers comprising an assemblage of segments fixed to the hull around the stern bearing boss, said segments having ribs extending in the longitudinal direction of the propeller shaft and over the space between the said boss and propeller boss, and cutter serrations formed on the longitudinal edges of the ribs and segments.

7. Guard device for ships' propellers comprising a segment of stepped formation attached to a bearing boss and adapted for extending into the space between the bearing and propeller bosses, and inclined rib formations on said segments said rib formations having cutter teeth disposed along their length substantially as set forth.

8. Guard device for ships' propellers comprising a segment of stepped formation attached to a bearing boss, a projection on said segment adapted for extending over the space between the bearing and propeller bosses, and an inclined toothed cutter formation on said segment and said projection substantially as set forth.

9. Guard device for ships' propellers comprising a segment attachable to a bearing boss the said segment being formed with inwardly and outwardly presented serrated cutter edges, those outwardly presented being adapted for severing an entanglement winding around the shaft in either direction substantially as set forth.

FREDERICK JOHN BLAKE.
